COMBINED SEWING CHEST AND PIN CUSHION OR THE LIKE

Hubert J. Barrows, Denver, Colo.

Application April 4, 1952, Serial No. 19,197

Term of patent 14 years

(Cl. D3—19)

To all whom it may concern:

Be it known that I, Hubert J. Barrows, a citizen of the United States, residing at the city and county of Denver, State of Colorado, have invented a new, original, and ornamental Design for a Combined Sewing Chest and Pin Cushion or the like, of which the following is a specification, reference being had to the accompanying drawing, forming a part hereof.

Figure 1 is a front elevation of my new design for a combined sewing chest and pin cushion or the like.

Figure 4 is a sectional view as taken on the indicated line 4—4 at Fig. 1 but showing the holder cover or lid in raised position.

I claim:

The ornamental design for a combined sewing chest and pin cushion or the like, as shown.

HUBERT J. BARROWS.
